[57] CLAIM

The ornamental design for a fluid container, as shown and described.

DESCRIPTION

FIG. 1 is a perspective view of a fluid container showing our new design;

FIG. 2 is a front elevation thereof;

FIG. 3 is a left side elevation thereof with the right side elevation being a mirror image thereof;

FIG. 4 is a top plan view thereof;

FIG. 5 is a bottom plan view thereof; and

FIG. 6 is a partially fragmented front elevation of a modified form of FIG. 2.
